UNITED STATES PATENT OFFICE.

JOHANN GOTTLIEB LEBERECHT BORMANN, OF CHARLOTTENBURG, GERMANY.

GAS-GENERATOR.

No. 890,439.

Specification of Letters Patent.

Patented June 9, 1908.

Application filed May 20, 1907. Serial No. 374,742.

To all whom it may concern:

Be it known that I, JOHANN GOTTLIEB LEBERECHT BORMANN, of 28 Schlüterstrasse, Charlottenburg, near Berlin, Kingdom of Prussia, Germany, have invented new and useful Improvements in Gas-Generators, of which the following is a specification.

The invention relates to those generators in which the production of combustible gases is effected by the admission of the air required for combustion into the upper part of the generator shaft, while the complete gasification of the coal at the lower end of the generator shaft is effected by means of the introduction of steam. Hitherto in generators of this kind the eduction flues through which the combustible gas formed is conducted out of the generator were made very narrow and arranged in the walls of the generator shaft without any provision for cooling. Hence arose the drawback that these flues readily became choked up by the ashes and coke particles carried along with the gas, and that in particular the inside outlets of these flues were blocked up by the clinker and coke caking firmly on the hot walls of the generator shaft.

The subject matter of the present invention is to obviate this defect by a special form of the gas eduction flues and the provision of an intensive cooling arrangement of the lower parts of the generator shaft containing the gas eduction flues. For this purpose the apertures of egress and the eduction flues for the combustible gases are made as wide as possible and are built into a ring-shaped water boiler which surrounds on all sides the lower part of the generator shaft. In order to avoid the accumulation of steam in this water boiler the top part of the latter is made to slope steeply up towards a steam collecting reservoir fitted above, preferably at the side. The steam boiler may conveniently be divided into several ring-shaped parts adapted to the shape of the generator and the eduction flues, which parts have openings interconnecting them, and possess such a shape that they penetrate far into the spaces to be cooled or approach them as closely as possible so that an effective cooling of the latter is insured.

The accompanying drawings are in illustration of my invention, Figure 1 being a section, Fig. 2 a longitudinal section along the line A—A and Fig. 3 a longitudinal section along the line B—B of Fig. 1.

The generator *a* has a filling funnel *b* above and a grate *d* below. The upper opening *c* serves for the introduction of the required air for combustion. Immediately beneath the grate and opening out into the latter is arranged the box-shaped large-dimensioned tube *w*, which is connected by a piping *v*, *k*, with the steam collecting chamber of a steam boiler *i*. The vertical tube *w* has its lower open end immersed in the ash-pit *e* filled with water, so that it is water-closed.

The eduction flue *f* for the combustible gases produced in the generator lies ringwise round the lower part of the generator immediately above the grate. It leads into the collecting flue *h*, which, surrounding the steam pipe *v*, *k*, opens out above into the gas eduction pipe *l*.

Around the gas eduction flue *f* and the lower parts of the generator shaft *a* the ring-shaped water boiler *g* is fitted. The latter is in connection with the water space of the steam boiler *i* and consists of an inside and an outside ring, which communicate with each other by means of connecting apertures *z*. The water boiler *g* projects into the inside of the generator shaft; its upper part is made to rise in the form of a funnel so that the steam or water vapor developed by the absorption of heat is conducted upwards into the steam boiler *i*, and the boiler *g* is constantly filled with water in all its parts. Hence the lower parts of the generator shaft lying above the grate which are formed by the walls of this water boiler *g*, as well as the gas eduction flue *f* built into this boiler and traversed by water circulation tubes of the boiler, are cooled on all sides by water.

The funnel *b*, for the fuel replenishment, carries at its lower end a valve shutter *p*, which can be made so substantially as to act as a ramming device in order to remove any interstices or hollow spaces in the layer of fuel. Its motion is regulated by the lifting contrivance *q*.

The generator operates as follows: After the shaft has been filled with fuel and fire has been started, air is admitted at *c* and the gas drawn off at *l* by suitable means, in consequence of which the temperature of the burning fuel on the grate is increased and the water in the boiler *g* begins to vaporize. The steam thus produced is conducted through the piping *h*, *v* and the tube *w* to the grate and passes the latter. The steam coming in contact with the incandescent fuel is gasified

and together with the gaseous products of the burning fuel is drawn off through the eduction flue *f*, the collecting flue *h* and the conduit *l* to the place of utilization.

Having now particularly described and ascertained the nature of my said invention and in what manner the same is to be performed, I declare that what I claim is:

1. In a gas generator a fuel shaft, having air inlet ports at the top and a grate arranged adjacent to the lower end thereof, an eduction flue for the gas produced above said grate, a water boiler surrounding the lower part of said shaft and said eduction flue, said boiler consisting of two ring-shaped members disposed one above the other, and having a ring-shaped slit between them surrounding the lower end of said shaft and forming the eduction flue.

2. In a gas generator a fuel shaft having air inlet ports at the top and a grate arranged adjacent to the lower end thereof, an eduction flue for the gas produced above said grate, a water boiler surrounding the lower portion of said shaft and said eduction flue, said boiler consisting of two ring-shaped members arranged one above the other and having a ring-shaped slit between them surrounding the lower end of said shaft and forming said eduction flue, said members being connected one with the other by means of pipes passing through said slit.

3. In a gas generator a fuel shaft having air inlet ports at the top and a grate arranged adjacent to the lower end thereof, an eduction flue for the gas produced above said grate, a water boiler surrounding the lower part of said shaft and said eduction flue, said boiler consisting of two ring-shaped members arranged one above the other, and having a ring-shaped slit between them surrounding the lower end of said shaft and forming said eduction flue, one of said members projecting into the interior of said shaft and thereby forming a ring-shaped contraction of said shaft.

4. In a gas generator a fuel shaft having air inlet ports at the top and a grate arranged adjacent to the lower end thereof, an eduction flue for the gas produced above said grate, a water boiler surrounding the lower part of said shaft and said eduction flue, said boiler consisting of two ring-shaped members arranged one above the other and having a ring-shaped slit between them surrounding the lower end of said shaft and forming said eduction flue, said members being connected one with the other by means of pipes passing through said slits, the upper ring-shaped member projecting into the interior of said shaft and forming a ring-shaped contraction thereof.

5. In a gas generator a fuel shaft having air inlet ports at the top and a grate adjacent to the lower end thereof, an eduction flue for

the gas produced above said grate, a water boiler surrounding the lower parts of said shaft and said eduction flue, said boiler consisting of two ring-shaped members arranged one above the other, and having a ring-shaped slit between them and surrounding the lower end of said shaft and forming said eduction flue, one of said ring-shaped members projecting into the interior of said shaft and forming a ring-shaped contraction thereof, said projecting part being inclined to the inside of said shaft to cover partially the ring-shaped entrance of said slit.

6. In a gas generator a fuel shaft having air inlet ports at the top and a grate arranged adjacent to the lower end of said shaft, an eduction flue for the gas produced above said grate, a water boiler surrounding the lower parts of said shaft and said eduction flue, said boiler consisting of two ring-shaped members arranged one above the other and having a ring-shaped slit between them surrounding the lower end of said shaft and forming said eduction flue, said members being connected by means of pipes passing through said slits, one of said ring-shaped members projecting into the interior of said shaft, said projecting part being inclined to the interior of said shaft to cover partially the ring-shaped entrance of said slit.

7. In a gas generator a fuel shaft having air inlet ports at the top and a grate arranged adjacent to the lower end of said shaft, an eduction flue for the gas produced above said grate, a water boiler surrounding the lower part of said shaft and said eduction flue, said boiler consisting of two ring-shaped members arranged one above the other, said members having arranged between them said eduction flue in form of a ring-shaped slit surrounding the lower end of said shaft, a collecting flue beneath said boiler, said slit being of a shape to form a conduit ascending from the entrance above the grate and then curved down and leading into said collecting flue.

8. In a gas generator a fuel shaft having air inlet ports at the top and a grate arranged adjacent to the lower end of said shaft, an eduction flue for the gas produced above said grate, a water boiler surrounding the lower part of said shaft and said eduction flue, said boiler consisting of two ring-shaped members arranged one above the other, said members having arranged between them said eduction flue in form of a ring-shaped slit surrounding the lower end of said shaft, said members being connected one with the other by means of pipes passing through said slit, a collecting flue beneath said boiler, said slit being of a shape to form a conduit ascending from the entrance above the grate and then being curved down and leading into said collecting flue.

9. In a gas generator, a fuel shaft having

air inlet ports at the top and a grate arranged adjacent to the lower end of said shaft, an eduction flue for the gas produced above said grate, a water boiler surrounding the lower 5 part of said shaft and said eduction flue, said boiler consisting of two ring-shaped members arranged one above the other, said members having arranged between them said eduction flue in form of a ring-shaped slit 10 surrounding the lower end of said shaft, the upper one of said parts projecting into the interior of said shaft thereby forming a ring-shaped contraction of said shaft, a collecting flue beneath said boiler, said slit being of a 15 shape to form a conduit ascending from the entrance above the grate and then being curved down and leading into said collecting flue.

10. In a gas generator a fuel shaft having 20 air inlet ports at the top and a grate arranged adjacent to the lower end of said shaft, an eduction flue for the gas produced above said grate, a water boiler surrounding the lower

part of said shaft and said eduction flue, said boiler consisting of two ring-shaped members arranged one above the other, said members having arranged between them said eduction flue in form of a ring-shaped slit 25 surrounding the lower end of said shaft, said members being connected one with the other by means of pipes passing through said slits, the upper one of said parts projecting into the interior of said shaft thereby forming a ring-shaped contraction of the same, a collecting flue beneath said boiler, said slit 30 35 being of a shape to form a conduit ascending from the entrance above the grate and then being curved down and leading into said collecting flue.

In testimony whereof I have hereunto set 40 my hand in presence of two subscribing witnesses.
